UNITED STATES PATENT OFFICE.

FRANK W. SKINNER, OF WEST NORWOOD, NEW JERSEY.

LIQUID INDICATOR.

Application filed December 5, 1923. Serial No. 678,719.

My invention relates to improvements in liquid gages, and more particularly has reference to a gage adapted for indicating the height of a liquid such as gasoline in a container upon a vehicle such as a motor car or boat, at a convenient place such as in front of the operator upon the dashboard or the like.

In the accompanying drawings, I have illustrated in Fig. 1 in front elevation, a suitable form of indicator embodying an application of my invention. Fig. 2 is a side view. Fig. 3 is a longitudinal section on the line 3—3 of Fig. 1. Fig. 4 is a plan view of the casing or housing. Fig. 5 a plan view of the interior casing, and Fig. 6 a side view thereof. Fig. 7 is a longitudinal section of a suitable form of threaded connection.

The frame or casing 14 is preferably cast of metal and is provided with a base chamber 8 communicating with a back channel 9 having laterally projecting lugs 10 in staggered arrangement as shown in Fig. 4. 11 indicates a tapered chamber communicating with the channel 9 and terminating in a threaded connector 12 in communication with chamber 11 through the opening 13. Within the casing 14 shown to advantage in Fig. 4 may be seated the inner casing 15 shown to advantage in Figs. 5 and 6, and in the base of which is secured a tube 16 communicating with the channel 17 which in turn opens into the rectangular recess 18, the tube 16 seating in the rear of the base portion of the chamber 8 as shown in Fig. 3. Before the frame 15 is placed within the rectangular opening 19 of the casing 14, a suitable gasket of paper 20 is preferably laid upon the ledge 21 having been suitably saturated with glue, shellac, or other suitable material, and the two frames are then pressed together until securely sealed. In the top of the inner frame a suitable opening 22 is provided and the same is adapted when the parts are assembled to register with the opening 23 in the top of the frame 14, and also communicates with the opening 24 in the cup member 25, which cup member 50 is externally threaded as indicated at 26 and is provided with a spring such as 27 which rests upon the annular flange or ledge 28 of the casting as shown. 29 indicates a button having a piston base 30 adapted to be reciprocated within the cylinder or tube 31

and which is normally projected by the spring 27, and 32 indicates a cap or ring through which said button 29 projects and which is threaded upon the interior as indicated at 33 to receive a cap such as 34 for sealing the same when the button is pressed inwardly against the spring 27 for shipment.

When assembled, the face 35 of the inner frame 15 is covered with a gasket of paper 65 suitably saturated with glue, shellac, or other suitable material, after which a plate of glass such as 36 is pressed thereon until securely sealed, and then the escutcheon or face plate 37 may be applied. This plate is provided with suitable studs such as 38 which enter the recess such as 39 in the casing and which studs are drilled and tapped to receive screws adapted to pass through the back of the casing as indicated at 40, thereby securely assembling the complete indicator.

When applying the same to a dashboard or other suitable support upon a vehicle, a hole is drilled of a diameter sufficient to receive the chamber 8, and a second hole is drilled above sufficiently to allow for the passage of the chamber 11 after which a suitable bolt may be passed over the coupling 12, thereby securely holding the indicator in position and leaving the connection 12 clear for connecting on the air tube which passes to the tank containing the gasoline or other liquid to be measured. For purposes of shipment and to prevent loss of liquid, a key plug such as 41 tapped at the inner end as indicated at 42 may be introduced into the coupling 12 as shown in Fig. 7 and screwed down tight so as to prevent any loss of liquid. In applying the gage it is held upright before the plug 41 is removed. This allows the liquid to drain back into the reading chamber 18 and base chamber 8 and variations of air pressure in the line connecting the tank with the inlet connector 12 pass down through the air space 9, thereby causing the liquid in the chamber 8 to rise or fall through the tube 16, channel 17, and reading space 18 accordingly as the height of the liquid varies in the tank. For purposes of rectification, and to replace possible air loss in the line, the button 29 which is perforated as indicated at 43 may be pushed and the air compressed with the compression of the spring 27 passes down 105 110

through the channel 23—22 and through the liquid, thereby balancing the air line so as to insure correct reading.

Of course it will be understood that various modifications may be made in the construction and arrangement of parts without departing from the spirit of the invention as claimed.

I claim:

- 10 1. In a gauge of the class described, a casing having a liquid well in the base, a transparent front portion, a column of liquid behind said front adapted to be observed therethrough, said column communicating with said well, there being a passage from said well to the liquid to be gauged and means in said passage for retarding flow of air between said well and the liquid to be gauged, push button pump means adjacent the top and on the front of said gauge for admitting and forcing air through said column, well and said air retarding means, said push button pump means when inoperative, providing escape for air above the top of said column, and a cap for sealing said push
- 15 20

button means when inoperative, providing escape for air above the top of said column.

2. In a gauge of the class described, a 25 casing having a liquid well in the base, a transparent front portion, a column of liquid behind said front adapted to be observed therethrough, said column communicating with said well, there being a passage from 30 said well to the liquid to be gauged and means in said passage for retarding flow of air between said well and the liquid to be gauged, push button pump means adjacent the top and on the front of said gauge for 35 admitting and forcing air through said column, well and said air retarding means, said push button means when inoperative, providing escape for air above the top of said column, and a cap for sealing said push 40 button means.

In testimony whereof I hereunto affix my signature.

FRANK W. SKINNER.
